UNITED STATES PATENT OFFICE.

WILLIAM GOLD NEWMAN, OF OGDEN, UTAH.

SCREEN-WIRE-CLOTH RACK.

1,144,230.

Specification of Letters Patent. Patented June 22, 1915.

Application filed September 12, 1913. Serial No. 769,515.

To all whom it may concern:

Be it known that I, WILLIAM G. NEWMAN, a citizen of the United States, and a resident of Ogden, in the county of Weber and State of Utah, have made certain new and useful Improvements in Screen-Wire-Cloth Rack, of which the following is a specification.

My invention relates to improvements in racks for displaying and dispensing screen wire cloth or other material put up in rolls, and it consists in the combinations, constructions, and arrangements herein described and claimed.

An object of my invention is to provide means for displaying wire cloth of various width.

A further object of my invention is to provide means for unrolling the cloth and for cutting off squarely pieces drawn from the roll.

A further object of my invention is to provide means for accurately measuring the amount of wire screen cloth cut off.

Other objects and advantages will appear in the following specification, and the novel features of the device will be particularly pointed out in the appended claims.

My invention is illustrated in the accompanying drawings forming part of this application in which—

Figure 1 is a perspective view of the device, Fig. 2 is a plan view of the bottom of the cutting table, Fig. 3 is a side view of the cutter, Fig. 4 is an end view of the cutter, Fig. 5 is a section along the line 5—5 of Fig. 2, Fig. 6 is a face view of the measuring device, Fig. 7 is a section through the measuring device, Fig. 8 is a face view showing the interior mechanism of the measuring device, Fig. 9 is a section through a portion of the device showing the manner of securing the shields, Fig. 10 is a section through the shields, and Fig. 11 is a section through one of the shields at right angles to Fig. 10.

In carrying out my invention I provide a base portion 1 bearing the uprights 2. These are connected by upper longitudinal members 3 and transverse end members 4. All but the upper transverse members are provided with slots 4^x to receive the shafts or spindles 5 which extend from the cross members at one end to the cross members at the other. These spindles 5 bear shields 6 of the shape shown in Fig. 11. In this figure it will be noted that the shields are substan-

tially cylindrical in shape and have a closed end 6^x. A sleeve 6^y is secured to the end 6^x and is provided with a set screw 6^z. On the inside of a shield is a hub 6^a. Each shaft or 60 spindle 5 is provided with two of these shields, the open end of the shields facing each other. Each shield is provided with an outlet portion 6^b on the lower side of the shield facing the front of the device. It will be noted that the slots 4^x at the rear of the device are deeper (see Fig. 10) than those at the front. This permits the rear shafts 5 to be mounted lower than the front shafts 5, thus bringing the 70 outlet portions 6^b of the rear shields below those of the front shields. The primary purpose of these shields is to prevent an abnormal unwinding and consequent expansion of a roll of screen wire cloth from the 75 inner end while permitting its unwinding and withdrawal at the outer end. Furthermore the shields themselves, due to the fact that the roll tends to expand, forms a holding member, which while holding the wire 80 cloth so as to prevent the outer edge from retracting at the same time permits it to be pulled forwardly with ease when the cloth is to be sold.

Secured to the uprights 2 are the front 35 longitudinal bars 7^a, 7^b and 7^c between adjacent end members 4, while at the rear in alignment with the bar 7^c is a bar 7^d. A top guide member 8^a is secured to the bar 7^a at its front edge. A central guide member 90 8^b is secured to the longitudinal bar 7^b. A bottom guide member 8^c rests upon the bar 7^c at the front end and upon the bar 7^d at its rear end. It will be noted that the outlet portion 6^b of the front shield 6 enters 95 between the upper guide member 8^a and the central guide member 8^b, while the outlet portion 6^b of the rear shield 6 enters between the central guide member 8^b and the bottom guide member 8^c. It will thus be 100 seen that between adjacent end members 4 is a pair of shields having guide means for the wire cloth. At one corner of each of the front uprights 2 is a rack 9, each of these racks being countersunk, as shown in Fig. 1. 105

The cutting table 10 is provided with a slot 10^x extending from end to end. This slot is T-shaped, as shown in Fig. 4. The table is secured to a U-shaped frame consisting of forwardly extending side arms 11 which 110 are joined at their ends by a cross bar 12. At the inner ends of the arms 11 which form

2
a portion of the frame of the cutting table is journaled a shaft 43, which is provided with a crank handle 44 at one end. The shaft 43 is also provided with a ratchet 45 which is engaged by a locking dog 46. Pinions 47 are carried by the shaft 43 and are arranged to engage the racks 9. At each end of the frame is a Y-shaped plate 48 bearing a roller 49 at the junction of the arms of the Y and rollers 50 at the ends of the arms. As will be seen from Fig. 1 the rollers 50 are arranged to engage the rear sides of the front uprights 2 while the rollers 49 are arranged to engage the front side. This forms a supporting means for the table which permits it to be raised vertically.

In Fig. 2 I have shown a winding roller 51 which is disposed between the arms 11. The shaft 51^x of the winding roller is designed to enter an opening 51^y (see Fig. 1) in one of the arms 11, the other arm being provided with a slot 51^z arranged to receive the shaft 51^x to which a handle 52 is connected. The winding roller 51 is provided with a slot 51^x running from end to end of the roller and arranged to receive one edge of the wire cloth. A U-shaped spring 54 is provided for holding the cloth in position on the winding roller, while a latch 51^w extends over the slot 51^x in the side member 11 for holding the shaft of the winding roller in place.

The cutter is formed by a slidable block 17 having a T-shaped base 17^x arranged to enter the slot 10^x in the table. A cutting knife 18 is pivoted at 19 on a pin which is provided with a spring 20 to hold the knife in position.

The measuring device consists of a bracket 21 (see Fig. 1) supported at one end of the table 10 and bearing a hinged arm 22 which supports the registering mechanism.

The registering mechanism consists of a casing 23 bearing at its lower end a composition roller 24 which is mounted to rotate on a shaft 25. The latter bears a pinion 26 arranged to engage a gear 27 on a shaft 28. The gear 27 carries an adjustable tooth 29 which is arranged to project in the path of a gear 30 on a shaft 31. The shafts 28 and 31 bear arms 28^x and 31^x respectively which are arranged to play over the faces of dials 32 and 33 respectively.

55 From the foregoing description of the various parts of the device the operation thereof may be readily understood.

The core rods 5 are removable from the slots 4^x. One of the end shields 6 is removed and a roll of screen wire cloth is placed upon the core rod 5, one end of the roll being inserted in one of the shields.

The other shield is then placed on the opposite end of the roll and secured in position by means of the set screw 6^y. All of

the rods 5 in the rack are thus supplied with rolls of wire cloth. The loose end of the wire cloth is then passed out between the guide members and is brought to the front of the device.

Now when a given amount of the wire cloth is sold the cutting table may be elevated to a position in alinement with the cloth to be cut by turning the handle 44. This will cause the turning of the pinions 47 which will engage the racks thus elevating or lowering the table in accordance with the direction in which the handle 44 is turning. The rollers 49 and 50 form anti-friction means for easily manipulating the table. The measuring device is now lowered so as to bring the composition roller 24 in contact with the cloth. The edge of the cloth is now pulled forward and placed in the slot 51^x of the winding rod 51, and the handle 52 is turned until the dial on the measuring device indicates the desired amount. It will be observed that the lower dial is preferably graduated in inches, while the upper dial is graduated in feet. The cutter is now run forward and by means of the handle 18 the wire is cut, the slot 10^x forming a straight edge for the cutter so as to permit the wire to be cut squarely across.

When one roll is used up it may be replaced by another one. Since the front edges of the wire cloth are always exposed to view, one may rapidly make a selection of the cloth which he desires without the necessity of handling the roll at all. It will be seen therefore that the device provides a display rack as well as a dispensing rack. Owing to the measuring device there is no necessity of measuring the cloth by the use of a tape line or yard stick.

I claim:

1. In a screen wire cloth rack, a frame, a plurality of core rods carried by said frame, each of said core rods being adapted to loosely carry a screen wire cloth roll, and means carried by each core rod for preventing the unwinding of the roll from the inner end of the roll while permitting the unwinding of the roll from the outer end, said means comprising a pair of oppositely disposed cylindrical shields adapted to fit over the ends of the roll and to frictionally engage the sides of the roll, said shields having outlets for the wire cloth.

2. In a screen wire cloth rack, a frame, a plurality of core rods carried by said frame, each of said core rods being adapted to loosely carry a screen wire cloth roll, means carried by each core rod for preventing the unwinding of the roll from the inner end of the roll while permitting the unwinding of the roll from the outer end, said means comprising a pair of oppositely disposed cylindrical shields adapted to fit over the

ends of the roll and to frictionally engage the sides of the roll, said shields having outlets for the wire cloth, and means for adjusting the shields toward or away from each other and for securing them in their adjusted position.

3. In a screen wire cloth rack, a frame, a plurality of core rods carried by said frame, each of said core rods being adapted to 10 loosely carry a screen wire cloth roll, means carried by each core rod for preventing the unwinding of the roll from the inner end of the roll while permitting the unwinding of the roll from the outer end, said means

comprising a pair of oppositely disposed cylindrical shields adapted to fit over the ends of the roll and to frictionally engage the sides of the roll, said shields having outlets for the wire cloth, means for adjusting the shields toward or away from each other and 20 for securing them in their adjusted position, and guide means carried by the frame at the front end thereof for guiding the wire cloth removed from the shields.

WILLIAM GOLD NEWMAN.
